ward and his Attorneys.

UNITED STATES PATENT OFFICE.

RICHARD DEDERER, OF SINDELFINGEN, WURTTEMBERG, GERMANY, ASSIGNOR TO
WILLIAM LUETTGEN, OF NEW YORK, N. Y.

ELECTRIC CUT-OUT.

Application filed August 17, 1921. Serial No. 493,174.

To all whom it may concern:

Be it known that I, RICHARD DEDERER, a citizen of Germany, residing at Sindelfingen, Wurttemberg, Germany, have invented 5 certain new and useful Improvements in Electric Cut-Outs, of which the following is a full, clear, and exact description.

This invention relates to thermal cut outs. More specifically it relates to fuses and has 10 for one of its principal objects to provide means called into action upon blowing or rupture of the fusible element for indicating that the fuse has blown.

Another object is to provide a device of 15 the class above mentioned in which the indications of abnormality are visible at night, though the artificial illumination be poor or artificial illumination, other than that provided by the device, totally absent.

20 A further object is to provide a fuse of the type described in which access for the purpose of repair or renewal is facilitated. Further objects and advantages will appear as the invention is hereinafter disclosed.

25 Referring to the drawings which illustrate what I now consider a preferred physical embodiment of the invention:

Fig. 1 is a section taken substantially through the axis of a fuse plug embodying 30 one form of the invention.

Fig. 2 is a fragmentary longitudinal section taken substantially at right angles to the plane of the section shown in Fig. 1.

Fig. 3 is a plan view of the device with 35 certain parts removed.

Fig. 4 is a plan view of the complete device.

Fig. 5 is a view similar to Fig. 2 but illustrating the parts in the position they assume upon rupture of the fusible element. 40

Fig. 6 is a fragmentary detail section of a part of the structure shown in Fig. 2 but illustrating a slight modification.

While the invention may assume a variety of other forms, the device shown in the drawings possesses such marked advantages that I have selected it for the purpose of illustration and disclosure. This form of device may be constructed substantially 45 as follows:

A body portion *a*, of porcelain or other suitable insulating material, carries at its periphery the usual shell contact or threaded ring *b*, and at its lower end a center contact *e*, cemented or otherwise suitably se- 50

cured thereto. The shell *b* and contact *e* constitute electric terminals adapted electrically to engage cooperating contacts in a socket (not shown) of the usual type when the plug is mounted therein. The fusible element consisting of the fuse wire or link *d* is electrically connected, at one end, by solder or other suitable means, to the terminal *e*, and at its other end to one end of a conducting plate or strip *h*, in turn electrically connected to the terminal *b*. The fusible element *d* is shown extending from the terminal *e* through a channel *i*, provided in the body portion *a*, thence through notches *j*, thence to the upper end of the strip *h*. The strip *h* extends through a channel or bore *k* provided in the body portion. It will be noted that access to the channels *i* and *k* is readily had from the upper or outer end of the body portion. 75

The body portion *a* is also provided with a recess *m*, shown substantially rectangular in shape, and adapted to receive a portion of the indicating means. The latter comprises a substantially Z-shaped strip or 80 plate 10 and a substantially U-shaped spring member 11 engaging at one of its ends the upper part of the intermediate leg of the Z. It will be noted that the last mentioned leg of the U is angled over to form a seat 85

for that portion of the fusible element *d* which extends from one of the notches *j*, *j* to the other. The design and connections are such that when the fuse is in normal condition the member *c* is held, by the fusible element *d*, in the position shown in Fig. 2. When the fuse blows or the link *d* ruptures due to any cause the U-shaped member 11, by virtue of its inherent re- 90

siliency, automatically causes the parts to 95 assume the position shown in Fig. 5. The upper member *n*, by virtue of the two different positions it occupies, may therefore be employed as a device to indicate normality or abnormality in the condition of the fuse. 100

In order to make the different indications highly distinctive and readily readable I prefer to employ an indicating means of the changeable exhibitor type. I therefore provide the cover plate *f*, which is cemented or otherwise secured to the body portion *a*, with a sight opening *g* through which the target *n* is visible in one position of the latter and invisible in the other. In the particular arrangement illustrated the tar- 105 110

get n is visible through the sight opening g when the fuse is normal and invisible when the fuse has blown (see Figs. 2 and 5 respectively).

- 5 In order to render the two indications readily distinguishable in poor light or darkness I prefer to provide one or more of the indicating elements with light-emitting means. This may be effected by coating the 10 inner face of the plate f , which is preferably of glass, with a light-emitting, phosphorescent luminous paint and, if desirable, backing up this coating with an asbestos shield or disc α (see Fig. 6); the 15 sight-opening or window g being uncoated and therefore transparent. Preferably the upper or outer face of the target n is provided with a coating of luminous paint which may be similar to that applied to the 20 glass cover plate f .

The operation of the device disclosed above will now be clear to those skilled in the art. It may be summarized as follows: When the fuse is normal the parts will 25 occupy the position illustrated in Fig. 2 and the field f will present the appearance of an unbroken disc of comparatively light color whether viewed in strong or weak light. When the element d blows or ruptures, due 30 to excess current or any other cause, the parts assume the position shown in Fig. 5. The target n is then out of the line of vision through the sight-opening g and the latter appears as a dark spot on a light background. Therefore, when any one of a 35 group of fuses embodying my invention has blown, it may be readily located in view of its appearance, i. e., a dark spot upon a light field as distinguished from an unbroken light field.

It will be noted that the plate f serves also as a cover for channels i and k and the recess m . By removing the glass cover f access to the fuse interior may be had for 45 the purpose of repair or renewal after a fuse link has blown. The cost of repairs or renewals is therefore low and a considerable saving in material is effected. In order to facilitate checking, the glass f or its asbestos 50 backing member (if one is provided) may bear a serial number. Obviously if the backing α bears the serial number a suitable sight opening therefor would be provided in the paint on the glass f .

55 In accordance with the provisions of the patent statutes, I have herein described the principle of operation of my invention, together with the apparatus which I now consider to represent the best embodiments 60 thereof, but I desire to have it understood that the apparatus disclosed is only illustrative and that the invention may be carried out by other means and applied to other forms of fuses. Also while it is designed to use the various features and ele-

ments in the combinations and relations described, some of these may be altered and others omitted, within the scope of the appended claims, without interfering with the more general results and effects outlined, 70 and the invention extends to such use.

What I claim is—

1. A fuse plug comprising in combination, a body portion provided with a terminal at one end and a side terminal, said body portion having fuse receiving channels accessible from the outer end of said body portion and terminating at corresponding ones of said terminals, a fuse link extending through said channels and electrically connected to said terminals, indicating means within said body portion and controlled by said link, said indicating means being accessible from the outer end of said body portion, and a closure for the outer end of 85 said body portion.

2. A fuse comprising in combination, a body portion provided with a sight opening, an indicator mounted within said body portion for movement across said sight opening, a pair of stationary current-conducting elements carried by said body portion, a fuse link anchored at its opposite ends to said elements, and means controlled by rupture of said fuse link for moving said indicator. 90

3. A fuse comprising in combination, a body portion provided with a sight opening, an indicator mounted within said body portion for movement across said sight opening, a light-emitting substance carried by 100 said indicator, a pair of stationary current-conducting elements carried by said body portion, a fuse link anchored at its opposite ends to said elements, and means controlled by 105 rupture of said fuse link for moving said indicator.

4. A fuse comprising in combination, a body portion provided with a sight opening, an indicator mounted within said body portion for movement across said sight opening, a pair of current-conducting terminals carried by said body portion, resilient means 110 for actuating said indicator, and means comprising a fuse link for conveying current from one of said terminals to the other without causing current to flow through said resilient means, said resilient means being controlled by said fuse link. 115

5. A fuse comprising in combination, a body portion and fuse link carried thereby, an indicator, a leaf spring mounted in said body portion and adapted when released to operate said indicator, said spring being normally held in flexed condition by said fuse link, and means for conveying current to and from said fuse link without causing it to flow through said spring. 120

6. A fuse comprising in combination, a body portion and fuse link carried thereby, 125

an indicator, a leaf spring mounted in said body portion and adapted when released to operate said indicator, said spring being normally held in substantially U-shaped flexed condition by said fuse link, and means for conveying current to and from said fuse link without causing it to flow through said spring.

7. A fuse plug comprising in combination, a body portion having a recess accessible from the outer end of said plug, an indicating device and spring for moving the same mounted in said recess, and a fuse link having a portion extending across said recess adjacent the outer end of the plug and normally opposing the action of said spring.

8. A fuse plug comprising in combination, a body portion having a recess accessible from the outer end of said plug, a normally substantially Z-shaped indicating device and normally substantially U-shaped spring for moving the same mounted in said recess, and a fuse link extending across said recess and normally opposing the action of said spring. 20 25

In testimony whereof I hereto affix my signature.
